UNITED STATES PATENT OFFICE.

BERNARD WISTROM, OF STROMSBURG, NEBRASKA.

WEATHER AND DUST PROOFING DEVICE.

1,192,361.

Specification of Letters Patent. Patented July 25, 1916.

Application filed April 7, 1916. Serial No. 89,687.

To all whom it may concern:

Be it known that I, BERNARD WISTROM, a citizen of Sweden, residing at Stromsburg, in the county of Polk, in the State of Nebraska, have invented certain new and useful Improvements in Weather and Dust Proofing Devices, of which the following is a specification.

This invention relates to improvements in weather and dust proofing devices of the type usually applied to doors to fill the space between the bottom of the door and the door sill when the door is closed.

The invention consists in the novel combination and arrangement of parts to be hereinafter fully described in the following specification, pointed out in the appended claims and illustrated in the accompanying drawing which forms a part of said specification and in which—

Figure 1 is an end view of my invention showing its application to a door, the door being closed. Fig. 2 is a view of the device about to be applied to the door. Fig. 3 is a sectional perspective view of the invention in use. Fig. 4 is a top plan view of the device. Fig. 5 is an inverted plan view of the same.

Like reference characters denote corresponding parts throughout the several views.

The reference numeral 1 denotes a strip of material having its lateral edges bent almost parallel to the body portion as at 2 and 35 flared at their terminations as at 3, 3. The body portion of the strip is formed with parallel rows of depressions 4. Lateral angle pieces are provided for engagement with the lateral edges of the strip 1, each angle 40 piece comprising the sides 5, 6, which are disposed substantially at right angles to each other, the sides 5 being formed with the integral teeth 7, spaced from each other, and the sides 6 being bent inwardly with 45 relation to the sides 5 to form the curved terminal lips 8 between which and the said sides 6 the lateral edges of the strip 1 are

disposed. The edges of a strip of rubber, or similar material, 9 are inserted between the lips 8 and the body portion of the strip 1 and by said members frictionally retained in position, the central portion of the rubber strip being bulged outwardly and downwardly as at 10 for frictional engagement with the sill 11 when the door is in closed relation. The angle pieces 5, 6 are secured to the door 12 by embedding the teeth 7 therein. The device being co-extensive with the base of the door and the door sill, it is obvious it will serve to prevent dust, drafts 60 of air and the like from passing between the door and sill when the door is closed.

What is claimed is:—

1. A weather and dust proofing device comprising oppositely disposed toothed angle pieces formed with adjacent looped lateral terminations, a strip having bent lateral portions inserted into said looped lateral terminations and a flexible element frictionally retained between said looped lateral terminations and said strip and formed with an outwardly and downwardly bulged portion.

2. A weather and dust proofing device comprising oppositely disposed angle pieces each of which is formed with right-angled sides, teeth formed on one of said sides, a lip formed on the other of said sides of each angle piece to form a loop therewith; a strip formed with curved lateral portions having flared terminations disposed in the said loops, and a flexible strip having its lateral edges frictionally retained between said loops and the aforesaid strip and its central portion bulged outwardly and downwardly 80 between the said angle pieces.

In testimony that I claim the foregoing as my own I have hereto affixed my signature in the presence of two subscribing witnesses.

BERNARD WISTROM.
